UNITED STATES PATENT OFFICE.

LENA GOLDFARB AND BARNEY GOLDFARB, OF EAST VICTOR, NEW YORK.

DESIGN FOR TOY HOUSE.

Application filed July 23, 1924. Serial No. 10,242. Term of patent 7 years.

To all whom it may concern:

Be it known that we, LENA GOLDFARB and BARNEY GOLDFARB, both citizens of the United States, residing at East Victor, in the county of Ontario and State of New York, have invented a new, original, and ornamental Design for Toy Houses, of which the following is a specification, reference being had to the accompanying drawing forming a part thereof.

We claim:

The ornamental design for toy house, as shown.

LENA GOLDFARB.
BARNEY GOLDFARB.
